MEANS FOR TREATING SUBSTANCES

Henri George, Paris, France, assignor to Societe Anonyme des Manufactures des Glaces & Produits Chimiques de Saint-Gobain, Chauny & Cirey, Paris, France

Application June 4, 1934, Serial No. 728,825
In France June 8, 1933

1 Claim. (Cl. 22—79)

This invention relates to a method and means for treating substances which are readily attacked by air when in a hot state and relates more particularly to means for melting and casting magnesium, its alloys and compounds, aluminum and other metals and materials, which are readily oxidizable when they are heated or when they are in a molten state.

It is known in prior art to fuse a metal in a furnace and to pour the molten metal into a mold which is temporarily connected with this furnace. It was found, however, that in many instances the metal which solidifies in the mold is defective, due to the fact that the gaseous atmosphere in the mold is different from that in the furnace, and also because the molten metal is exposed to outside air while it is poured from the furnace into the mold.

An object of this invention is to improve the processes of melting and casting magnesium and other substances by regulating in substantially the same manner the nature and the pressure of the gaseous medium passing over the molten substance both in the furnace and in the mold and by preventing the molten substance from coming in contact with the outside air while it is being poured out of the furnace and into the mold.

The above and other objects of this invention may be realized through the provision of two air tight containers which serve as a furnace for melting the magnesium and a mold for the molten substance, and through the provision of means interconnecting the interiors of the two containers in parallel and in such manner that gaseous currents of substantially the same nature and the same pressure may pass through the two containers, separate means being provided to pour the molten substance from one container into the other container without exposing it to outside air.

It is advisable to use a rotatable electrical furnace for melting the magnesium since in furnaces of this type the molten substance is not subjected to attack by gases resulting from the combustion of the heating means of a furnace of the usual type.

The invention will appear more clearly from the following detailed description when taken in connection with the accompanying drawings showing a preferred embodiment of the inventive idea.

In the drawings:

Figure 1 shows a furnace in side elevation and partly in section.

Figure 2 is a section along the line 2—2 of Figure 1, looking in the direction of the arrows.

Figure 3 shows on a larger scale and in section the mold attached to the furnace and the device for connecting the interior of the furnace with the mold.

In the drawings, a furnace 5 is provided with a metallic cylindrical casing 6 surrounding a layer of heat insulating material 7 as well as a lining 8 made of a refractory material. The external cylindrical casing 6 is closed at its two ends by two covers 9 and 10 which are rigidly connected with the casing 6 by angle irons 11.

A heating rod or resistance 12 is situated within the furnace 5 and is supported at its two ends by insulators 13 and 13a. Terminals 14 and 14a are connected with the ends of the heating rod 12 and may be connected with a source of electrical energy which is not shown in the drawings.

A casing 4 supports the insulator 13 and is carried by a support 15. A similar casing 4a supports the insulator 13a and is carried by the support 15a.

The furnace 5 is supported by two pairs of rollers 16 and 17. The rollers 17 (Fig. 2) are carried by supports 17a and are in engagement with an annular guide 18 which is rigidly connected with the casing 6. The rollers 16, only one of which is shown in the drawings, are carried by the support 16a and engage an annular guide 19 which is rigidly connected with the casing 6.

The furnace 5 is rotated by a toothed wheel 20 which meshes with a toothed annular crown 21, rigidly attached to the casing 6. The toothed wheel 20 is driven by a motor 22 through the medium of several gear wheels situated within the gear box 23.

While the furnace 5 is rotated, the electrode 12 and the casings 4 and 4a remain stationary. A sufficient amount of packing material 24 is provided between the cover 9 and the casing 4 to prevent the outside air from penetrating into the interior of the furnace 5.

Similar packing material 25 is provided between the cover 10 and the casing 4a. Air-tight packing material 26 is also provided between the casings 4 and 4a and the insulators 13 and 13a.

A mold 30, shown on a larger scale in Figure 3, comprises a lower portion 33, which is detachably connected with the upper casing 34 by flanges 35 and bolts 36. The mold casing 33 is connected with the casing 34 in such manner

that atmospheric air cannot penetrate into the interior of the mold. The upper casing 34 is connected with the casing 6 by rivets 31 passing through a flange portion 32 of the casing 34.

5 Any number of removable mold casings 33 may be attached, one after the other, to the casing 34.

The interior 37 of the furnace 5 is connected with the interior 38 of the mold 30, by a passage 39. This connection may be interrupted 10 by a conical stopper or plug 40, fitting into a correspondingly shaped portion of the passage 39.

The plug 40 is attached to one end of a threaded rod 41. The opposite end of the rod 15 41 is rigidly connected with a piston 42 which is slideable within a hollow tubular casing 43. The opposite end of the tube 43 projects through a wall of the casing 34 and is provided with a handwheel 44. A stuffing box nut 45 surrounds 20 the tube 43 and is screwed into an opening formed in a flange 46 which constitutes a part of the casing 34. Suitable packing material 47 is placed around the tube 43 between the stuffing box nut 45 and the flange 46 to prevent atmospheric air from penetrating into the interior 25 of the casing 34. The end 48 of the tube 43 is provided with inner screw threads meshing with the screw threads of the rod 41 and is carried by a sleeve 49 which is attached by a bolt 50 to 30 a wall of the upper mold casing 34.

The casing 4a is provided with a pipe 51 which carries a valve 51a and through which a gaseous current under any suitable pressure 35 may be introduced into the interior of the furnace 5. A similar pipe 52 provided with a valve 52a is connected to the casing 4 and serves as an outlet for the gaseous current after it has passed through the furnace.

A pipe 60 is attached to the cover 10 and 40 communicates with the interior of the furnace 5 at the point where the gas current enters into the furnace. The pipe 60 is connected with a pipe 61 the opposite end of which is connected with the casing 34. A valve 62 is carried by the pipe 45 61.

The opposite end of the casing 34 is connected with one end of the pipe 63 which is provided 50 with a valve 64. The pipe 63 is connected with another pipe 65 which is attached to the cover 9 and leads to the interior of the furnace 5 at the point where the gas current leaves the furnace.

Due to this arrangement the same gas current 55 which passes through the furnace 5 also passes through the mold 30 with the result that the molten magnesium both in the furnace 5 and in the mold 30 is subjected to the same treatment.

The device operates as follows:

Magnesium or other substance is placed into 60 the interior of the furnace 5; then the terminals 14 and 14a are connected with a source of electrical energy, so that an electrical current 65 passes through the electrode 12. The furnace 5 is rotated by means of the motor 22 driving the gear wheel 20 which meshes with the toothed crown 21.

While the furnace 5 is rotated, the lower mold casing 33 may remain attached to the upper casing 34 and may be rotated along with the furnace 5, as shown in Figure 1 of the drawings.

It is possible, however, to remove the mold casing 33 before the motor 22 is started and to attach the casing 33 to the casing 34 only after

the rotation of the furnace 5 has been terminated (Fig. 2).

In both instances, the passage 39 should be tightly closed by the plug 40 while the furnace 5 is being rotated to prevent the molten substance 70 from leaving the furnace.

The plug 40 is inserted into the passage 39 by the rotation of the hand wheel 44 which is rigidly connected with the tube 43. The tube 43 is prevented from shifting in the direction of its axis through the provision of a bolt 71 carried by the sleeve 49 and projecting into a groove 72 formed in the end portion 48 of the tube 43. The rotation of the end portion 48 provided with inner screw threads meshing with the screw 15 threads of the rod 41 is transformed into a movement of the rod 41 in the direction of its longitudinal axis, said rod being prevented from rotating through the provision of a pin 73 projecting into a longitudinal groove 74 formed in 20 the rod. Since the plug 40 is rigidly connected with the rod 41 it will move along with it.

The plug 40 is moved to the left (looking in the direction of Figure 3) to open the passage 39 after the completion of the melting process, 25 when the rotation of the furnace 5 has been interrupted and when the mold casing 33 has been securely attached to the upper casing 34.

The pipe 51 (Fig. 1) is connected with any suitable means not shown in the drawings, for 30 supplying a gaseous nonoxidizing current of a predetermined nature and having a predetermined pressure to the interior of the furnace 5. The gaseous current flows through the pipe 51 into the interior of the casing 4a. The main 35 portion of the current will flow through the furnace 5 in a direction toward the casing 4. A certain part of the current will pass through the pipes 60 and 61 into the interior of the mold 30, leaving the mold through the pipes 63 and 65. 40 The entire gaseous current leaves the furnace 5 through the casing 4 and the pipe 52.

Thus the molten substance 70, when flowing by gravity through the passage 39 into the interior 38 of the mold 30, is not exposed to out- 45 side air.

When the mold is filled with the molten substance, the plug 40 is again inserted into the passage 39, and after solidification of the substance in the mold, the mold casing 33 is separated from the casing 34 and the finished casting is removed from the mold casing 33.

What is claimed is:

Means for treating substances which are readily attacked by air when in a hot state, comprising in combination a rotatable air-tight furnace, a heating rod situated within said furnace and adapted to be heated by an electrical current, an upper casing firmly connected with said furnace and rotatable therewith, said upper cas- 60 ing being situated adjacent to a passage formed in said furnace for the molten substance, means carried by said upper casing for closing and opening said passage, a removable mold casing adapted to be connected in an air-tight manner 65 with said upper casing, said passage interconnecting the interiors of said furnace and said mold casing, and means connected with said furnace and said upper casing for passing gaseous currents of substantially the same nature and 70 pressure through said furnace and said mold casing.

HENRI GEORGE.
